UNITED STATES PATENT OFFICE.

ISRAEL MALASKY, OF JOHNSTOWN, PENNSYLVANIA.

RUG-DISPLAY DEVICE.

Application filed October 31, 1921. Serial No. 511,618.

To all whom it may concern:

Be it known that I, ISRAEL MALASKY, a citizen of the United States, residing at Johnstown, in the county of Cambria and 5 State of Pennsylvania, have invented new and useful Improvements in Rug-Display Devices, of which the following is a specification.

This invention relates to display devices 10 and has for its object the provision of a power driven device for displaying rugs which are arranged in piles, the arrangement being such as to throw back the successive rugs, beginning from the top, so as to 15 display the different patterns or samples to a prospective purchaser.

Ordinarily, rugs are arranged in piles and in order to display the successive ones to a prospective purchaser, it is necessary to 20 employ usually two operators or assistants to the salesman, who grasp the corners of the rugs and throw them back, beginning at the topmost one, so that any or all of the 25 rugs within the pile may be exhibited. This operation is laborious and, as above stated, requires two operators to carry out the process rapidly and efficiently. I am aware that there are display racks which hold the rugs in vertical position in suitable frames which 30 are rotatably mounted from a vertical support but there is a great disadvantage in this system of exhibition as considerable time and labor are involved in suspending the rugs and in subsequently removing them 35 from the display rack. Another disadvantage is that the rugs are all exposed more or less to the action of light which tends to fade them. It is with the above facts in view that the present invention has been 40 signed.

An important object is the provision of a power driven display device in which the rugs are simply piled upon a slightly elevated platform, means being provided 45 whereby successive rugs may be thrown back for display purposes, this means being furthermore reversible whereby to return the rugs to their normal position.

Another object is the provision of a device 50 of this character with which is associated means whereby all the rugs above the one selected by a purchaser may be elevated

bodily so that a desired rug may be withdrawn from the pile without difficulty and without disturbing the other rugs.

Another object is the provision of a novel 55 endless chain-carried gripping device which engages the edges of the successive rugs automatically for throwing them back in one direction or the other.

An additional object is the provision of a device of this character which will be comparatively simple and inexpensive in manufacture, highly efficient in use, durable in service, and a general improvement in the 60 art.

With the above and other objects and advantages in view, the invention consists in the details of construction to be hereinafter 65 more fully described and claimed and illustrated in the accompanying drawings in which

Figure 1 is a plan view of my complete rack.

Figure 2 is a side elevation thereof.

Figure 3 is a detail cross sectional view on the line 3-3 of Figure 2.

Figure 4 is a detail vertical cross sectional view.

Figure 5 is a detail view of the chain and 80 gripping device carried thereby.

Figure 6 is a view similar to Figure 5 but showing the gripping device in section.

Figure 7 is an elevation taken at right angles to Figure 5.

Figure 8 is a perspective view of the bar carried by each end of each rug.

Figure 9 is a perspective view of the lifting rod.

Figure 10 is a perspective view of one of 90 the knobs for holding the bars upon the rugs.

Referring more particularly to the drawings I have shown my device as comprising a frame which includes a pair of side members 10 which are formed of channel iron of the cross - sectional configuration shown. Each of these frames includes a bottom bar portion 11 from the ends of which rise vertical portions 12 from the upper end of 95

which extend converging inclined portions 13 which lead into the upper horizontal portion 14. These frames are mounted in upright position upon the floor, as by means of 100

suitable L-shaped brackets 15 secured to the lower portions 11. Suitably mounted with respect to these frames is a platform 16 which is elevated a slight distance above the floor. The various rugs to be exhibited are laid upon this platform in a pile in the ordinary manner.

Secured upon one end of each rug is an elongated metallic bar 17 held in position by means of a plurality of U-shaped spring clips 18. Owing to the increased thickness of these edges of the rugs on account of the addition thereof of the bars and clips, it is preferable that the platform 16 have one end curved and extending downwardly, as shown at 19.

Rising from the lower portions 11 of the frames 10 are brackets 20 formed with elongated slots 21 and associated with these brackets is an inverted U-shaped bar 22 which has its ends slidably engaged against the brackets 20 and adjustably secured thereto by screws 23 passing through the slots 21 and carrying wing nuts 24. By this means it will be seen that the bar 22 will clamp all of the rugs A firmly onto the platform so that longitudinal or lateral displacement will be prevented.

Journalized within the channel bars which 30 constitute the frames 10 and arranged at spaced intervals are sprockets 25 about which are trained endless chains 26. One pair of sprockets 25 has its shaft 27 carrying a sprocket 28 about which is trained a drive 35 chain 29 trained about a sprocket 30 on the shaft of an electric motor 31 or other conventional power device.

Carried by the chains, which are of course driven at the same speed, are gripping devices, naturally arranged in pairs, and it is preferable that two pairs be provided. Each gripping device comprises a shank 32 slideable through a bearing 33 carried by one of the links of the chain and carrying a block 34 of rectangular shape. Each gripping device further includes an elongated head 35 which is slideable transversely of the shank 32 and block 34 and which has a recess of greater length than the block 34, for a purpose to be hereinafter made apparent, the head furthermore having its ends formed as cam noses 37. It is preferable that the block 34 be formed with recesses 38 within which are located spring-pressed balls 39 engaging within recesses 40 in the head 35 for normally holding the head and block in a predetermined position at either limit of the movement of the head with respect to the block and shank. I also provide a coil spring 41 which engages against the bearing 33 and the adjacent face of the head 35 so that the head and block may yield with respect to the chain.

The operation of the device is as follows; 65 Assuming that a pile of rugs has been

placed upon the platform 16 and that each rug has one end provided with the bar 17 held thereon by the clips 18, and assuming that all the rugs are in truly superposed relation as shown in Figure 2, whenever the 70 salesman desires to display the successive rugs to a prospective purchaser, it is merely necessary that he set the motor 31 in operation whereupon it is of course apparent that the endless chains 26 will be driven owing 75 to the drive connection above described. As the chains travel along the channeled frames 10 in the direction indicated by the arrow, the gripping members carried by the chains will of course pass over the contact 80 bars 17 carried by the rugs. Regardless of the position in which the block 34 and heads 35 occupy relatively to each other, initially, when the cam nose 37 of the gripping devices of each pair engages against the lowermost one of the bars 17, the heads 37 will be moved downwardly with respect to the blocks 34 which are incapable of such movement with respect to the chains and this will of course result in leaving a gap between 90 the lower end of the block 34 and the adjacent cam nose of the head. The gripping devices will of course pass over all of the superposed bars 17, the spring 41 being, incidentally under tension and the shank 32 95 being slid through the bearing 33 as shown in Figure 5, until the gripping device passes over the uppermost bar 17 on the pile of rugs. As the movement continues and the gripping devices come opposite the uppermost bar 17, the springs 41 will operate to force the gripping devices inwardly toward each other and this will of course result in the ends of the lower cam noses engaging against the ends of the uppermost bar 17 with 100 105 this bar subsequently slipping into the spaces between the lower ends of the blocks 34 and the lower cam noses, as indicated by dotted lines in Figure 6. As the chains continue to travel about the frames 10 it will be apparent that the gripping devices will carry the uppermost bar 17 and consequently the uppermost rug A along with the chains so that the rug will be folded back upon itself with the bar 22 acting as the pivot or turning point of the rug. Located in the frames 10 are cam projections 10^a which are engaged by the grippers when the rug is thrown back, the grippers being thereby 110 pressed back so as to release the rug. As 115 the chains are continued to be driven, it is apparent that when the gripping devices make a complete circuit of the frames 10 they will engage and carry over the next rug in exactly the same manner, the successive rugs being thus displayed to the prospective purchaser until all the rugs in the pile have been folded over in the ordinary manner.

After the rugs have been displayed, they 130

are returned to original position by reversing the movement of the chains. I may provide cam projections at the left side of the frame to release the grippers if preferred, 5 though if any rugs have not been folded back or over, the engagement of the grippers with the ends of the bars thereof will effect the releasing action.

When a certain rug has been selected and 10 it is desired to remove the same from the pile, it is extremely desirable that such action be accomplished without disturbing all the rugs in the pile. In order to accomplish this, I provide a pair of upstanding socket 15 members 42 in association with each of the frames 10 and slidably within each of these socket members is an upwardly extending rack bar 43 carrying a laterally extending hook 44. Each socket member is provided 20 with a slot into which extends a pinion 45 carried by a shaft 46 having its free end provided with a gear 47 driven by a pinion 48. This shaft and gearing are the same at both sides of the device except that only 25 one handle 49 and gear 48 are provided. The shafts 46 at opposite sides of the frame carry bevel gears 50 meshing with bevel gears 51 carried by a shaft 52 which extends transversely of the frame so that when the 30 handle 49 is rotated both of the shafts 46 will be rotated for effecting vertical movement of the racks 43.

After the successive rugs have been thrown back to expose the certain rug selected, I 35 make use of bars 53 which are passed between the selected rug and the one next thereabove and which have their ends engaged with the hooks 44. The operator then turns the handle 49 and consequently effects 40 vertical movement of the racks 43 so that the rods 53 will elevate all the rugs above the one selected, whereupon the desired one may be easily withdrawn from the pile by pulling it out from between the 45 frames. It will be noted that it is necessary to deal with only one half the length of the rugs above the one selected. After a rug has been withdrawn, the gearing is operated in the reverse direction to return the 50 pile to lowered position, and the rods 53 are removed.

From the foregoing description and a study of the drawings, it will be apparent that I have thus provided a simply constructed and consequently inexpensive device by means of which the successive rugs in a pile may be easily displayed by a salesman alone and without the assistance of any additional operators, porters, or the like, for 55 effecting the throwing back of the successive rugs to display those next beneath. It is to be noted that the mechanism is reversible so that after the rugs have been displayed they may be returned to normal position and 60 be ready for the inspection of the next cus-

tomer. Owing to the provision of the power mechanism for effecting the throwing back it will be apparent that the operation involves no manual labor. Owing to the simplicity of construction and the fewness of parts, it is 70 apparent that there is very little to wear out and that the device should consequently be durable and have a long and satisfactory life.

While I have shown and described the 75 preferred embodiment of my invention, it is of course to be understood that I reserve the right to make such changes in the form, construction and arrangement of parts as will not depart from the spirit of the invention or the scope of the subjoined claims.

What is claimed is:—

1. A display device of the character described comprising a pair of end frames of channel iron formation, a platform located between said frames for supporting a pile of rugs in normally superposed relation, elongated bars to be secured upon all the rugs at one end thereof and having their ends projecting into said channel frames, 80 sprockets within said channeled frames, endless chains trained about said sprockets and simultaneously driven, and gripping members carried by said chains for engagement with the successive bars comprising shank 85 members slidably associated with the chains, blocks carried by said shank members, and heads slidably associated with the block members and having cam noses.

2. A display device of the character described comprising a pair of end frames of channel iron formation, a platform located between said frames supporting a pile of rugs in normally superposed relation, elongated bars to be secured upon all the rugs at one end thereof and having their ends projecting into said channeled frames, sprockets within said channeled frames, endless chains trained about said sprockets and simultaneously driven, gripping members carried by said chains for engagement with the successive bars comprising shank 95 members slidably associated with the chains, blocks carried by said shank members, and heads slidably associated with the block 100 members and having cam noses, the heads being formed of recesses of greater length than the length of the blocks whereby to provide recesses engageable upon the end 105 portions of said bars.

3. A display device of the character described comprising a pair of end frames of channel iron formation, a platform located between said frames supporting a pile of rugs in normally superposed relation, elongated bars to be secured upon all the rugs at one end thereof and having their ends projecting into said channeled frames, sprockets within said channeled frames, 110 endless chains trained about said sprockets 115 and gripping members carried by said chains for engagement with the successive bars comprising shank members slidably associated with the chains, blocks carried by said shank members, and heads slidably associated with the block 120 members and having cam noses, the heads being formed of recesses of greater length than the length of the blocks whereby to provide recesses engageable upon the end 125 portions of said bars.

and simultaneously driven, gripping members carried by said chains for engagement with the successive bars comprising shank members slidably associated with the 5 chains, blocks carried by said shank members, and heads slidably associated with the block members and having cam noses, a pair of slotted upright supports rising from the lower portions of said end frames, and 10 an inverted U-shaped bar slidably adjustably connected with said supports and extending over the pile of rugs at the center thereof.

4. A display device of the character described, comprising a pair of end frames of channel iron formation, a platform located between said frames supporting a pile of rugs in normally superposed relation, elongated bars to be secured upon all the

rugs at one end thereof and having their 20 ends projecting into said channeled frames, sprockets within said channeled frames, endless chains trained about said sprockets and simultaneously driven, gripping members carried by said chains for engagement with 25 the successive bars comprising shank members slidably associated with the chains, blocks carried by said shank members, and heads slidably associated with the block members and having cam noses, a plurality 30 of vertically movable rack bars associated with each frame and carrying hooks, and rods insertable through the pile of rugs and having their ends engageable within said hooks.

In testimony whereof I affix my signature.

ISRAEL MALASKY.
